METHOD AND APPARATUS FOR FREEZING
LIQUID CARBON DIOXIDEJustus C. Goosmann, Chicago, Ill., assignor, by
mesne assignments, to Adico Development Cor-
poration

Application October 24, 1928, Serial No. 314,644

14 Claims. (Cl. 62—121)

This invention relates in general to apparatus and a method used in connection therewith for freezing liquid carbon dioxide into solid form.

One of the objects of this invention is the provision of an apparatus and a method for use in connection therewith which are relatively simple and yet highly efficient in use.

A further object of this invention is the provision of a system in which carbon dioxide gas is placed under high pressure in several stages of compression and in which the gas is cooled after each compression operation by a counter-flow of cooler gas from another part of the system.

A further object of this invention consists in the reduction in pressure of the gas after its delivery from the last compression operation in several stages of pressure reduction in which the gas flows from a liquid receiver and several liquid coolers in succession.

Another object of this invention is to provide a liquid cooler in which the liquid carbon dioxide is cooled by external evaporation of a portion of the liquid carbon dioxide and heat transfer through the intervening walls of the cooler while at the same time maintaining a higher pressure of the liquid which thus becomes sub-cooled below the pressure at which it is maintained whereby any gaseous bubbles in the liquid will be condensed and liquefied.

A still further object of this invention contemplates the delivery of the liquid from the last liquid cooler to a freezing machine under such conditions of temperature and pressure that the liquid is maintained in a liquid state.

A further object of this invention contemplates the building up of a suitable pressure in the freezing machine so that the liquid delivered thereto will be maintained at a temperature and pressure above its triple point to prevent premature freezing of the liquid.

A still further object of this invention contemplates a sudden reduction in pressure in the freezing machine after sufficient liquid is delivered thereto to effect freezing of the liquid.

Another object of this invention is the provision of a liquid freezing machine of a construction which is relatively simple and adapted for efficient and rapid use in effecting the freezing of liquid carbon dioxide.

A still further object of this invention is the provision of means in connection with the freezing machine whereby the frozen block of carbon dioxide may be readily removed therefrom.

A still further object of this invention involves the use of pressure reducing valves in different

parts of the system for effecting the desired reductions in pressure as the gas and liquid progresses therethrough.

These and other objects, as will appear from the following disclosure, are secured by means of this invention. 5

This invention resides substantially in the combination, construction, arrangement, relative location of parts, steps and combinations of steps, all as will more fully appear in the following disclosure when taken in connection with the drawings and set forth in the appended claims. 10

Referring to the drawings for illustrated examples of the principles and structures involved in this invention, 15

Figure 1 is a diagrammatic view with some parts in cross section showing the general combination of elements comprising the system of this invention and employing the process thereof;

Fig. 2 is a vertical cross-sectional view through the freezing machine showing the relative association of all the parts;

Fig. 3 is a vertical cross-sectional view of one form of pressure reducing valve adapted for use in the system of this invention; 25

Fig. 4 is a longitudinal cross-sectional view through one form of liquid cooler, inter-cooler or heat exchangers adapted for use in the system of this invention; and

Fig. 5 is a cross-sectional view through one of 30 the mixing chambers.

The general considerations underlying the operation and use of a system of the type of this invention, as well as the principles of operation and physical philosophy underlying its use have 35 been disclosed in considerable detail in my co-pending application, Serial No. 298,992 filed August 11, 1928. It seems, therefore, unnecessary to set forth these considerations in detail in this application except such departures therefrom and additions thereto which are peculiar to the operation of this apparatus. These considerations will be discussed in connection with the disclosure of the apparatus in detail and the operation thereof. 40

The general distinction in this procedure lies in the fact that instead of forming the liquid carbon dioxide into snow and then compressing it into blocks the liquid is frozen directly into solid form by means of a liquid freezing machine 50 rather than a snow forming machine.

Referring now to the drawings there is disclosed at 1 a pipe leading from any suitable source of carbon dioxide gas through which the warm gas at approximately 5 pounds gauge pres- 55

sure and a temperature of approximately 80° F. is delivered to the mixing cylinder 2. The mixing cylinder consists simply of a closed chamber as do the other mixing cylinders to be mentioned and described later. A pipe 3 connects the mixing cylinder with the first compressor comprising a cylinder 4 and piston 5. This compressor, like the other compressors to be mentioned later, presents the ordinary type of compressor having two opposed valves as indicated in the drawings, one of which (the left-hand valve) opens on the suction stroke of the piston (downwardly in Fig. 1), and the other (the right-hand valve) opens on the compression stroke of the piston (upwardly in Fig. 1) causing a compression of the gas and its delivery to pipe 6.

As is well understood, only one of these valves is open at a time and are so adjusted that the first compressor compresses the gas to a pressure of approximately 100 to 150 pounds pressure and a temperature of approximately 150° which is subsequently reduced in the inter-cooler 7 and by the admixture of colder gas in the mixer 9 returning from other points in the system. The gas then flows from pipe 6 through the first inter-cooler 7. This inter-cooler comprises a pipe coil immersed in cold water, or it may have the form shown in Fig. 4 so arranged that cold water may flow thereover.

Liquid CO₂ may be used for cooling instead of water by external operation as for instance in liquid coolers 28 and 31. Other suitable cooling means may also be used. The gas is then cooled to approximately 80° F. and flows through pipe 8 to the mixing chamber 9 where it is further cooled to about 30° by the cold gas entering the mixer through pipes 46 and 49. From this mixing cylinder the gas flows into cylinder 11 of the second compressor through pipe 10. Piston 12 compresses the gas to a pressure of approximately 350 to 450 pounds gauge from whence it is delivered through pipe 13 to the second inter-cooler 14, in which its temperature is again reduced to about 30° by cold gas entering the mixer 18 through pipes 45 and 17. The gas then flows through pipe 15 to coil 16 of the heat exchanger 43. The gas is cooled still further in coil 16 and then delivered to the third mixing cylinder 18 through pipe 17. Pipe 19 connects cylinder 18 with the third compressor 20 where the gas is compressed by piston 21 to approximately a pressure of 1000 pounds gauge and a temperature of 140 to 150° F. This gas is then delivered through pipe 22 to the condenser coil 23 where it is sufficiently cooled to change it into a liquid as it flows through the connection having the control valve 24 to the liquid receiver 25. This liquid is then delivered at a temperature of approximately 80° through pipe 26 to the first liquid cooler 28 through the pressure reducing valve 27. This valve is of the type shown in Fig. 3 and will be described in detail later. This valve effects a reduction in pressure of from approximately 900 to 1000 pounds gauge to approximately 350 to 400 pounds gauge whereby its temperature is automatically reduced to about +10°. The liquid is then delivered to the second liquid cooler 31 through pipe 29 in which is the second pressure reducing valve which effects a reduction in pressure of from approximately 350 to 400 pounds gauge and a corresponding temperature to a pressure of about 150 pounds and a temperature around -40° F.

During the operation of reducing the pressure of the liquid as it flows from cylinder 25 to cyl-

inder 28 some gas is formed which is delivered through pipe 45 to mixing cylinder 18 where it mixes with the warmer gas coming from the second compressor and as a result cools it. It is the cooled mixture flowing from mixing cylinder 18 which is compressed in the third compressor. A connection 46 extends from cylinder 31 and conducts the gas formed in the pressure reduction effected by valve 30 to mixing cylinder 9 where the relatively cooler gas mixes with the relatively warmer gas coming from the first compressor. It is this mixture of gases which is compressed by the second compressor. The cooled liquid flows from cylinder 31 through pipe 32 in which is the pressure reducing valve 33 to the liquid freezing machine 35. The liquid in passing through valve 33 is reduced from a pressure of approximately 150 pounds gauge to 60 pounds gauge and an equivalent temperature of approximately -70° F. For liquid carbon dioxide a pressure of 60 pounds gauge and a temperature of -70° F. represents the critical temperature of the liquid at which, or below which, the liquid automatically changes into the solid phase. The liquid may also be cooled by external evaporation and heat transfer through a metallic wall.

However, in order to prevent the premature reduction in pressure and temperature of the liquid as it flows into the liquid freezing machine it is necessary to build up a pressure within the machine before the liquid is delivered thereto. This is effected through pipe 90 and valve 91 which leads into the interior of the machine and through which carbon dioxide gas may be introduced from any suitable source, for instance, from pipe 46 as shown, so that the pressure within the machine may be built up to approximately 150 pounds gauge.

Since the pressure in cylinder 31 is at approximately from 150 pounds upward gauge valve 91 can be a pressure reducing valve which effects a reduction of pressure in the gas to approximately 100 pounds gauge so that the pressure within the liquid freezing machine will not be built up above that amount. A pipe 49 having the valve 50 therein connects the liquid freezing machine with the mixing cylinder 9. Valve 50 may be of the type shown in Fig. 3 and acts in this case as a sort of a check-valve as will be described in detail later. Pipe 47 and its valve 48, which is an ordinary valve, is connected to any suitable point in the system, as for example to pipe 15, so that warm gas may be delivered to the liquid freezing machine for a purpose to be disclosed later. Pipe 38 having the valves 39 and 40, which are ordinary control valves or quick acting valves, connect the freezing machine through valve 42 and pipe 41 with the heat exchanger 43 or directly to low pressure mixer 2 through pipe 41 for a purpose to be disclosed later.

The liquid freezing machine will now be disclosed in detail referring particularly to Fig. 2. The machine is shown comprising a casing 51 having an inner conically formed wall 51 united at its top with the top of the casing 51 and likewise at the bottom, as indicated at 53. The top of casing 51 is provided with a number of openings 52. Pipe 32, which extends into the casing within the inner wall, is provided with a suitably formed branch 58 having openings at the ends so that the liquid as it flows through these openings will fall onto the sides of wall 51 and flow downwardly without creating too much agitation thereof. As clearly shown, pipes 90 and 49 ex-

tend through the casing 57 and open into the space between it and the wall 51. Pipe 38 is connected in a similar manner to the interior of casing 57 as is pipe 41. A sight glass 36 is connected in the space within wall 51 to give a visual indication of the height of the liquid within the machine.

The lower end of the casing is normally open and is adapted to be closed by means of a removable cover 37 and hinged bolts 56 by means of which a tight seal may be formed in conjunction with the gasket or washer 55. The top and sides of the machine are covered with a heat insulating casing 54 of any suitable material, such as hair felt for instance.

The construction of the pressure reducing valve is shown in Fig. 3 and comprises a body member 60 having a passage 61 and a passage 62 separated from each other by means of a valve. A removable cover member 63 is attached to the casing 60 and is provided with a hollow extension which is threadedly engaged by means of the tube 64 having a cap 65 attached to its upper rim by means of threads. A threaded rod and hand wheel 66 extends through the cap 65 and contacts with the member 61 engaging the upper end of spring 68. The lower end of spring 68 rests upon a disc 69 which is, in turn, supported by a flexible diaphragm rigidly held at its periphery between the members 60 and 63. Diaphragm 70 rests upon a button 73 slidably mounted in a member 71 which is threadedly supported in the wall of member 60 separating passages 61 and 62. The button 73 is provided with an extension 74 forming a valve which controls the passage 80 extending through the threaded extension of member 71. A spring 75 tends to maintain the button 73 and the valve in raised position. The pressure caused by spring 68 upon disc 69 and diaphragm 70 may be varied by means of the stem and hand wheel 66. In each case in which the valve is used the high pressure connection is made to passage 62. The gas or liquid then flows into the upper chamber to which passage 62 is connected and through the small openings 72 in member 71 where it is stopped by valve 74. The pressure of the gas in this chamber also tends to raise diaphragm 70 and does so when the pressure is sufficient to overcome the opposition of spring 68.

When this occurs the raising of diaphragm 80 permits spring 75 to raise button 73 and valve 74 so that the gas may flow through passages 72 and 80 into the lower chamber to which passage 61 connects. This effects a reduction in pressure and temperature of the gas in a well known manner. Valves 27, 30, 33, 39 and 42 all operate in this manner. Valve 50 is of the same construction but is intended to operate not only as a pressure reducing valve but also as a sort of check-valve.

The heat exchanger shown in Fig. 4 is adapted for use as an inter-cooler or liquid cooler. It is shown comprising a cylindrical casing 100 having an inlet and an outlet 101 and 102. The casing is provided with the removable heads 103 and 105 provided with connections 104 and 106, respectively. Near each end of the casing is a transverse wall which support between them the pipes 108 opening therethrough to establish communication between the chamber at each end of the casing. At the lowest point in the casing a drain valve is provided. When the device is used as an inter-cooler, the cooling fluid passes through pipes 108 and the gas travels through the shell

around the pipes. When used as a liquid cooler, the liquid to be cooled passes through the tubes 108, either in parallel or in series, while the cooling medium as evaporating liquid CO_2 passes through the shell around the tubes or it may be reversed to suit conditions. The drain valve acts to remove water, oil or other impurities.

The mixing cylinders can be of the construction shown in Fig. 5 and made of large extra heavy pipe. The mixing cylinder 9 is shown having the pipe connections 8, 10, 46 and 49. A drain valve, as before, is provided to remove water, oil and other impurities. Special separators and filters may be added to the pipe system to remove traces of oil, water and other impurities.

When liquid CO_2 is employed in the heat exchanger, it may be so arranged that the liquid is cooled by external evaporation of CO_2 reducing its temperature, while at the same time maintaining its higher pressure. The liquid CO_2 evaporated by this method of liquid cooling may be returned to the corresponding mixer in the same manner and at the same pressure which applies when the liquid is cooled by the evaporation of a part of the liquid in the said container.

In this way the economy of the process is practically maintained without a change in pressure.

The operation of the device will now be given. The operation to the point where the liquid is delivered to cylinder 31 has already been given in detail in connection with the description of the apparatus. With valve 34 closed, gas is delivered through pipe 90 to the liquid freezing machine until the pressure within it is built up to approximately 100 pounds gauge. Valve 34 is then opened and liquid is delivered from cylinder 31 into the machine against the pressure within the machine at sufficient pressure to cause the gas to flow out through pipe 49, it being understood that valves 39, 40, and 48 are closed. Valve 33 is set so that the liquid at a reduced pressure is delivered to the machine at a pressure sufficient to overcome the pressure of the gas within the machine. It is, of course, apparent that if necessary or desirable the pressure within the machine may be varied at will. Valve 50 is so set that the pressure of the liquid coming into the liquid freezing machine is sufficient to permit the escape of the gas within the machine through valve 50. This valve should also be set with a view to having the pressure of the gas at the proper value for delivery to mixing cylinder 9. When sufficient liquid has been delivered to the machine, as indicated by the sight glass 36, valve 34 is closed.

Valves 39 and 40 are then opened and the pressure within the machine is suddenly reduced far below the critical point of 60 pounds gauge and -70° F . Valve 42 is preferably of the quick opening and closing type so as to deliver the gas through pipe 41 to the heat exchanger 43 at the proper pressure, or when desirable through pipe 41a for a sudden pressure drop. In view of the construction of the machine as disclosed it is apparent that the gas therein can escape through pipe 38 without permitting the escape of the liquid which is confined within the inner wall 51. The sudden reduction in pressure and temperature to or below the critical values, permits or causes the liquid to flash into its solid condition. When the liquid has solidified, valve 34 being closed, cover 37 may be removed. If the solidified carbon dioxide sticks to wall 51 a little warm gas may be sent through pipe 41 to warm wall 51 so that the solid block is loosened and falls out 75

by reason of the conical shape of wall 51. The device is then ready for a repetition of the above procedure.

One highly important function of the pressure reducing valve in each case is to prevent the depletion of gas or liquid from the source from which it is flowing to the valve. Thus when the pressure of the gas or liquid falls below a predetermined value spring 68 will effect the closing of valve 74 so that the source cannot be depleted below a certain predetermined value.

One of the very important features of the process and the apparatus for carrying it out involves the idea of suddenly dropping the pressure in the ice forming machine to a complete and rapid solidification of the CO₂ therein.

I am, of course, well aware that many details are subject to change without departing from the scope and principles of this invention and I do not, therefore, desire to be strictly limited to the specific illustrations given in the drawings and specification for purposes of illustration and description. It is, of course, apparent that the relative pressure and temperatures may be varied through a considerable range within the scope of this invention and the steps and combinations thereof may be varied without departing materially therefrom.

I do not, therefore, desire to be limited in the scope of my invention except as required by the appended claims.

What I seek to secure by United States Letters Patent is:

1. In an apparatus of the class described, the combination comprising means for subjecting and maintaining the gas under such pressure and temperature as to liquefy it, means for gradually reducing the pressure and temperature of the liquid, including pressure reducing valves adapted

40 to maintain a predetermined pressure in said means for gradually reducing the pressure and temperature of the liquid, means connected to said means for gradually reducing the temperature and pressure for receiving the liquid under 45 a pressure and temperature above the triple point of the liquid, and means for reducing the pressure and temperature of the body of liquid in said receiving means below their critical values to effect solidification of the body of liquid therein.

50 2. In an apparatus of the class described, the combination comprising means for subjecting and maintaining the gas under such pressure and temperature as to liquefy it, means for reducing the pressure and temperature of the liquid to cool the same, including a pressure reducing valve adapted to maintain a predetermined pressure in said means, solidifying means for receiving the cooled liquid from said pressure and temperature reducing means at a liquid sustaining pressure, and 55 means for suddenly reducing the pressure and temperature on the body of liquid in said solidifying means below their critical values to effect solidification of the body of liquid.

60 3. In an apparatus for solidifying gases, the combination comprising a plurality of compressors, connections between each compressor, a cooling coil and mixing cylinder in the connections between the first and second compressor and the second and third compressor, means connected to the third compressor for causing the compressed gas to liquefy, a series of tanks connected to said means having connections therebetween including pressure reducing valves, said pressure reducing valves maintaining the pressure in the 65 last tank at a liquid sustaining pressure, connec-

tions between said mixing cylinders for returning gas to the latter, and a solidifier connected to the last tank for receiving liquid therefrom, said solidifier including means for maintaining a liquefying pressure therein for charging of the 5 solidifier with a body of liquid from said last tank.

6. In apparatus for solidifying gases, the combination comprising a plurality of compressors, connections between each compressor including a 10 cooling coil and means connected to the last compressor for causing the compressed gas to liquefy, a plurality of tanks connected to said means, said tanks having pressure reducing connections therebetween, connections from said tanks to said mixing cylinders for returning gas from the tanks to the cylinders, a solidifier including a solidification chamber therewith connected with and receiving liquid from the last of said plurality of tanks, a connection between the chamber of said 15 solidifier and one of said mixing cylinders for returning gas from the solidifier to the cylinder, and means in said connection for maintaining a pressure in said solidification chamber to enable 20 charging said chamber with liquid. 25

5. In apparatus for solidifying gases, in combination, multi-stage gas compressing means, means for liquefying compressed gas from said compression means, a solidifier having a solidification chamber therewith receiving liquefied 30 gas from said liquefying means, a gas offtake line from the solidification chamber of said solidifier to an intermediate stage of said multi-stage compression means for maintaining in the solidification chamber a liquid sustaining pressure whereby the chamber can be charged with a body of liquid, and means for releasing the liquid sustaining pressure in said solidification chamber to cause evaporation of the body of liquid therein with resultant solidification of a portion thereof. 40

6. In apparatus for solidifying carbon dioxide and the like, multi-stage compression means for compressing carbon dioxide gas to a pressure at which it will liquefy, means for condensing the compressed gas to liquefy it, a carbon dioxide 45 solidifier having a solidification chamber therein for receiving liquid carbon dioxide from said condensing means, means interposed between the condensing means and the solidifier for reducing the pressure of the liquid to lower its temperature, connections between said pressure reducing means and the multi-stage compression means for returning the cold gases from the pressure reducing means to the compression means, an expansion gas offtake from the solidification 55 chamber to said compression means, a valve in said connection for maintaining a pressure in the solidification chamber at which such chamber can be charged with liquid carbon dioxide, and means for releasing the pressure on a charge of 60 liquid carbon dioxide in the solidification chamber to evaporate the liquid and freeze out a portion thereof to solid form, said means returning the expansion gases from the solidification chamber to the multi-stage compression means. 65

7. The method of solidifying carbon dioxide, including increasing the pressure of carbon dioxide gas in several stages of compression, cooling the compressed gas after each stage of compression and mixing it with the cooler gas, subjecting the compressed gas after the last stage of compression to pressure and temperature conditions to liquefy the compressed gas, gradually reducing the pressure and temperature of the liquid thus formed in successive stages, collecting 70 75

5 a body of the reduced pressure and temperature liquid carbon dioxide in a closed chamber while maintaining a liquid sustaining pressure in such chamber by withdrawing gas from the chamber to an appropriate compression stage, and after charging the chamber with a body of liquid carbon dioxide reducing the liquid sustaining pressure in the chamber to cause the liquid to evaporate and freeze out a portion thereof as a solid 10 10. by withdrawing the evaporation gases to the low pressure compression stage.

8. In apparatus for solidifying carbon dioxide the combination comprising means for compressing and liquefying carbon dioxide, a plurality of 15 receivers connected to said liquefying means to receive liquid carbon dioxide therefrom, connections between said receivers, means associated with said receivers for effecting a pressure and temperature reduction on the liquid in each receiver, said means adapted to prevent reduction of pressure below a liquid sustaining pressure, a carbon dioxide solidifier having a solidification chamber connected with and receiving liquid from the last of said receivers, a gas offtake connection 20 between the solidification chamber of said solidifier connected with said carbon dioxide gas compressing means to maintain a pressure in the chamber at which the chamber can be charged with a body of liquid carbon dioxide, and means 25 for releasing the liquid carbon dioxide sustaining pressure in the solidification chamber after the latter has been charged with liquid whereby the liquid is evaporated to freeze out a portion thereof as a solid, said pressure releasing means with- 30 drawing the evaporation gas from the solidification chamber for return to the compression and liquefying means.

9. In apparatus for solidifying a gas, the combination comprising, means for compressing and liquefying the gas, a receiver connected with said gas liquefying means to receive liquid therefrom, means associated with said receiver for effecting a pressure and temperature reduction on the liquid in the receiver, said means adapted to prevent reduction of pressure below a liquid sustaining pressure, a solidifier having a solidification chamber connected with and adapted to receive liquid from said receiver, a gas offtake between the solidification chamber of the solidifier 45 and said gas compressing means to maintain a pressure in the chamber at which the chamber can be charged with a body of liquefied gas, means for releasing the liquid sustaining pressure in the solidification chamber after the latter has been charged with a body of liquid whereby the liquid is evaporated to freeze out a portion thereof as a solidified gas, and said pressure releasing means providing for withdrawal of the evaporation gas from the solidification chamber for return to the 50 gas compressing and liquefying means.

10. In apparatus for solidifying a gas, in combination, means for compressing and liquefying the gas, means for reducing the pressure and temperature of the liquefied gas to cool the same, 55 gas solidifying means for receiving and holding a charge of the cooled liquid from said pressure and temperature reducing means at a liquid sustaining pressure, and means for reducing the pressure and temperature of a charge of liquid held in the solidifying means below their critical values to effect solidification of the charge of liquid.

11. In apparatus for solidifying a gas, the combination including means for compressing and

liquefying the gas, a receiver connected with said gas liquefying means, means associated with said receiver for effecting a pressure and temperature reduction on the liquefied gas in the receiver, said means adapted to prevent reduction of the pressure below a liquid sustaining pressure in the receiver, a normally closed and gas-tight solidification chamber adapted to be charged with liquefied gas from the receiver, means connecting the receiver with the solidification chamber for discharging evaporation gas from the receiver into the solidification chamber to build up a liquid sustaining pressure in the chamber prior to charging the chamber with liquefied gas from the receiver, a gas offtake between the solidification 15 chamber and said gas compressing means for maintaining the liquid sustaining pressure in the chamber during charging with liquefied gas, and means for releasing the liquid sustaining pressure in the solidification chamber after the latter has been charged with liquid whereby the liquefied gas is evaporated to freeze out a portion thereof as solidified gas.

12. In gas solidifying apparatus, in combination, a source of liquefied gas, means for reducing the pressure and temperature of the liquefied gas from said source to cool the same, including a pressure reducing valve adapted to maintain a predetermined liquid sustaining pressure in said means, a gas solidification chamber for charging 30 with a body of cooled liquefied gas from said means at a liquid sustaining pressure in said chamber, means placing said chamber in communication with said pressure and temperature reducing means for discharge of evaporation gas 35 into the chamber to build up a liquid sustaining pressure therein prior to charging the chamber with liquefied gas, and means for reducing the pressure and temperature on a body of liquefied 40 gas in the solidification chamber below their critical values to thereby effect solidification of the body of liquefied gas in the chamber.

13. The method of solidifying carbon dioxide, including the steps of subjecting carbon dioxide gas to pressure and temperature conditions to 45 liquefy the gas; reducing the pressure and temperature of the liquefied gas to near the triple point of carbon dioxide; confining a body of the reduced pressure and temperature liquefied gas in a gas-tight chamber at substantially such near triple point pressure and temperature; and then reducing the pressure on the body of liquefied gas in the chamber to below the triple point while withdrawing the evaporation gases therefrom to 50 freeze out a portion of the body of liquid as a mass of solidified carbon dioxide in the chamber.

14. The method of solidifying carbon dioxide, including the steps of; subjecting carbon dioxide gas to pressure and temperature conditions to 60 liquefy the gas; reducing the pressure and temperature of the liquefied gas to near the triple point of carbon dioxide by expanding the liquefied gas in a closed container while withdrawing the evaporation gas to maintain the predetermined liquid sustaining pressure in the container; charging a gas-tight chamber with the reduced pressure and temperature gas from said container while maintaining the liquid sustaining pressure in such chamber; and reducing the pressure on the body of liquid in such chamber to 65 below the triple point to freeze out a portion of the liquid as a mass of solidified carbon dioxide.

JUSTUS C. GOOSMANN.
